UNITED STATES PATENT OFFICE.

J FRANK ALLARD, OF BROOKLYN, NEW YORK, ASSIGNOR TO UNDERWOOD TYPEWRITER COMPANY, OF NEW YORK, N. Y., A CORPORATION OF DELAWARE.

TYPE-WRITING MACHINE.

1,188,875.

Specification of Letters Patent. Patented June 27, 1916.

Application filed January 13, 1913. Serial No. 741,609.

To all whom it may concern:

Be it known that I, J FRANK ALLARD, a citizen of the United States, residing in Brooklyn, in the county of Kings and State of New York, have invented certain new and useful Improvements in Type-Writing Machines, of which the following is a specification.

This invention relates to means for type-writing in such foreign languages as employ vertical lines of writing instead of the ordinary horizontally extending lines of the English language.

One of the main objects of the invention is to produce a machine for writing Chinese by means of an alphabet consisting of forty or more characters, which has recently been devised for this purpose by certain authorities. The letters or characters forming this alphabet are not herein illustrated, because the machine is also adapted for writing other languages than Chinese. The machine is illustrated as adapted for writing a single case, for alphabets not provided with both capitals and small letters; no case shifting mechanism being shown.

It is customary in writing ordinary Chinese characters to place them one below another, beginning at the top of the page, so that the line of writing reads down the page; and this plan will be continued in connection with the new Chinese alphabet referred to.

This invention provides for the work-sheet to be moved vertically at the operation of the type-keys, so that the alphabet characters will be written on the work-sheet one below another, the top of each letter or alphabet character being adjacent to the bottom of the next letter or alphabet character, in contradistinction to the usual method of writing letters side by side as in English. Provision is also made for moving the work-sheet laterally for making spaces between the vertical lines of writing. According to the Chinese custom, the writing begins at the right-hand margin of the work-sheet and proceeds line-by-line toward the left-hand margin.

In carrying out the invention in its present form, the work-sheet is placed upon a revoluble cylindrical platen, which extends in a direction at right angles to the line of writing; and at the successive type key strokes, the platen is caused to rotate to ad-

vance the sheet so that the operation of the 55 keys causes the line of print to proceed from the top to the bottom of the sheet.

Preferably a spring is employed to rotate the platen for this purpose, and an escapement or letter-feeding mechanism controls the rotation of the platen effected by means of said spring. Upon the conclusion of a line of writing, a handle is drawn down for the purpose of rotating the platen back to initial position for beginning a new line 65 of writing and at the same time, the platen-rotating spring is re-wound.

The platen is preferably mounted upon a carriage which is moved step-by-step from left to right to make the spaces between 70 the lines; and this line-feeding mechanism is preferably operated by the same handle which rotates the platen backwardly to begin a new line of writing, so that immediately after said handle is operated, the writing of 75 the succeeding line may be begun. A separate key is also provided for line-spacing the platen whenever desired.

Preferably the platen-driving spring is placed upon the main framework of the machine, and connected by a train of gearing to the platen; said train including means which permits the line-spacing movement of the platen carriage without disconnecting the platen from its driving spring or from 85 its escapement mechanism.

Other features and advantages will hereinafter appear.

In the accompanying drawings, Figure 1 is a side elevation of the platen carriage, 90 showing a part of the train of gears which controls the rotation of the platen, and also showing a release key for said carriage. Fig. 2 is a front view of a spring barrel which rotates the platen and an escapement wheel 95 which is fast to said barrel; this figure also showing the type key-controlled dogs which control the step-by-step movement of said escapement wheel and platen. Fig. 3 is a sectional elevation taken about centrally 100 from front to rear of a typewriting machine embodying the present improvements. Fig. 4 is a detail sectional elevation of devices for automatically line-feeding the carriage during the backward revolution of the 105 platen to begin a new line of writing. Fig. 5 is a rear perspective view of a train of gearing which controls the letter-feeding ro-

tation of the platen. Fig. 6 is a side elevation of some of the members seen in Figs. 4 and 5. Fig. 7 is a perspective view of the line-feeding dogs, showing particularly a cut-away 83 in the ribbon-controlling universal bar frame which is operated by the type-keys, and which by reason of said cut-away is prevented from operating said line-feeding dogs. Fig. 8 is a plan of the type-operating keys and levers, and some of the gears which control the operation of the platen. Fig. 9 is a rear elevation of the rear part of the machine.

The drawings show an Underwood front-strike typewriter, which is used for convenience in illustrating the invention; said typewriter being however substantially modified for the purposes of the invention.

Alphabet keys 1 are mounted upon levers 2, fulcrumed at 3 and having returning springs 4; the levers having pin-and-slot connections at 5 with bell cranks 6, which have pin-and-slot connections at 7 with type bars 8, carrying alphabet types 9 to swing upwardly and rearwardly to strike upon the front side of a revolute platen 10; the type bars being mounted upon a curved fulcrum rod 11. The types 9 are intended for writing a foreign language, and correspond with foreign alphabet characters or letters on keys 1, which are illustrated diagrammatically at Fig. 8. The platen is not made to shift up and down, the machine being intended for use in writing foreign languages which do not have sets of both capital letters and lower-case letters; but the invention is not limited to the use of a single case of types.

The types strike through a ribbon 12, which is normally below the printing point, but which is lifted up at every type stroke to cover the printing point; there being for this purpose heels 13 provided on the type bars to engage a segmental universal bar 14, which forms part of a frame 15, that is mounted to be driven rearwardly by the heels 13 on the type bars 8; said universal bar at its rear end having arms 16 pivoted to the upper ends of upstanding arms 17, which are fast to a rock shaft 18; the front of the universal bar frame 15 being supported in the usual manner, and a spring 19 returning the universal bar frame 15 after actuation. Upon this universal bar frame 15 is fixed a slotted actuator 20 to engage a pin 21 upon the ribbon vibrating lever 22, which is pivoted at 23 upon the machine frame; said lever 22 carrying at its forward end an upright slide 24 to which is threaded the ribbon 12; for as the universal bar is driven back the slide or vibrator 24 is thrown up together with the ribbon, and hence the types make inked impressions upon the work sheet 25 which is carried around the platen 10.

As each character is printed, the paper is fed up, the platen 10 being revolved step-by-step for this purpose. This rotary letter or character spacing movement of the platen is controlled by the character keys 1. The power for rotating the platen is preferably supplied by a spring 26 (Fig. 2) contained in a barrel 27, which is connected by a train of gearing to the platen 10 to revolve the same, but which is controlled by an escapement wheel 28, the latter fixed upon the barrel 27 and co-operating with limber and detent dogs 29, 30. Dog 30 is mounted upon a rocker 31, through which extends a rock shaft 32 fast thereto; the rocker 31 being confined between ears 33, 34 fixed upon the frame work and serving as bearings for the rock shaft 32. This shaft is elongated and at its ends is journaled in bearings 35, 36; and it has at its ends a forwardly extending pair of arms 37, which are connected at their forward ends by a rod 38, which forms a second universal bar, and is pressed by a spring 39 up against the under sides of the key levers 2.

Whenever any key is depressed to operate its type, the universal bar 38 is depressed, and the dogs 29, 30 are vibrated forwardly; the escapement wheel 28 not being let off at this time, but the limber dog 29 being drawn to the right at Fig. 9 by means of a spring 40, so as to be in position to engage the next tooth of the escapement wheel 28. Upon the release of the key from pressure after the type impression is made, the spring 39 returns the universal bar 38 and the dogs 29, 30 permitting the escapement wheel 28 to advance one step and the spring 26 to rotate or drive the platen a corresponding distance.

The train of gearing between the spring barrel 27 and the platen may comprise a bevel gear 41 fixed on the spring barrel, a bevel pinion 42 in mesh therewith and mounted upon a vertical shaft 43, a bevel pinion 44 on the upper end of said shaft, a bevel pinion 45 fixed on a horizontal shaft 46 which is journaled in the machine frame, and a gear 47 fixed upon shaft 46 and meshing with a long barrel pinion 48 which is journaled by means of gudgeons 50 upon brackets 49 fixed upon the machine frame. This barrel pinion 48 may engage either of two pinions 51, 52, both of which are fast upon a horizontal shaft 53 extending from end to end of the platen frame or carriage 54. By means of intermediate pinions 55, 56, the pinions 51, 52 are connected to pinions 57, 58, fixed upon the axle 59 of the platen 10, and forming part of the gear train leading from the spring barrel 27. The platen frame or carriage 54 is mounted to move endwise for line-spacing; and when either pinion 51 or 52 moves out of mesh 130

with the barrel pinion 48, the other pinion always remains in mesh with pinion 48, so that a positive connection is maintained between the platen and the spring barrel 27 5 and its escapement devices, and hence the rotative position of the platen is always controlled.

The work sheet 25 may be held against the platen by any suitable means, as for instance front and rear feeding rolls 60, 61, 10 and a paper-guiding apron 62 of the usual type may also be provided.

At the completion of a vertical line of writing, the operator grasps a handle 63, 15 pivoted at 64 on the right-hand side of the machine frame, and throws the same downwardly from the dotted-line-position at Fig. 3 to the full-line position at Fig. 5, thereby both rewinding the spring 26 and revolving 20 the platen 10 backwardly to initial position; the limber dog 29 being swiveled at 65 (Fig. 2) in a manner common in type-writing machines, to permit the backward revolution of the letter-feeding escapement 25 wheel 28. The handle or arm 63 is connected to the spring barrel 27 by means of a sector 66, extending rearwardly from the pivot 64, and meshing with a bevel pinion 67, to which is fixed a pinion 68, meshing 30 with a gear 69 on the spring barrel 27.

It will be seen that the foregoing alphabet character or letter-feeding mechanism is effective to rotate the platen at every key stroke, regardless of the position of the 35 platen carriage, so that the writing of vertical lines on the work-sheet may proceed until the same is filled.

A non-printing word-spacing key or bar 70^a may be arranged across the machine in 40 front of the keyboard, and its levers or supports 70^b may extend back parallel with the type-key levers, and actuate the universal bar 38 at every depression of key 70^a; and these levers 70^b may, if desired, be 45 curved at 70^c to clear the bell cranks 6.

After the completion of any vertical line of writing, a key 71 may be pressed back for line-feeding the carriage 54, which 50 slides upon horizontal rails 72, 73 in the same manner as the paper carriage of said Underwood typewriting machine. This key 71 permits the carriage to be drawn along by a spring barrel 74 (Fig. 9), which is connected by a strap 75 to a pin 76 on the 55 carriage; said strap passing over a pulley 77 and forming a return loop, so that the spring barrel 74 draws the carriage from right to left, as seen at Fig. 9, which is a rear view. Viewed from the front of the 60 machine, the carriage is drawn from left to right at the line-spacing operation. This is useful for languages like Chinese and others, where the first vertical line of writing is made at the right-hand side of the 65 work-sheet or page, and in which the second

line of vertical writing is placed at the left of the first line of writing, and so on until the page is filled.

A rack 78 is connected to the carriage to mesh with a pinion 79, to which is connected 70 an escapement wheel 80, which is controlled by dogs 81, 82, which may be constructed and operated in a manner to resemble the letter-feeding dogs of said Underwood typewriting machine, with the exception 75 that they are not operated by the letter-feeding mechanism of the present machine; the universal bar frame 15 being cut-away as at 83 (Fig. 7) to avoid striking these dogs 81, 82.

At the completion of a page of writing, the carriage may be pressed back to the left, thus rewinding the spring barrel 74; the escapement wheel 80 being connected to the pinion 79 by means of pawls 84 (as usual in 85 the letter-feeding mechanism of said Underwood machine) to permit right to left movement of the carriage while the escapement wheel 80 remains stationary.

The carriage may be released to be set to 90 different line positions, by depressing a release key 85 on the carriage, which is connected to a bail 86 pivoted at 87 on the carriage and having thereon the line-feeding rack 78, which by depression of the key 85 95 is lifted from the pinion 79. Said line-feeding key 71 may be mounted on the forward end of a stem 88, to press rearwardly a lever 89, the latter pivoted at 90 upon the framework, and at its lower end connected 100 to a link 91, which extends rearwardly to an arm 92 pendent from a horizontal rock shaft 93. At its inner end said rock shaft carries an upstanding arm 94, which, when the key 71 is pressed back, engages the feeding pawl 105 or dog 82 to press the latter and the pawl or dog 81 rearwardly; and upon release of said key 71, a spring 95 returns the same, and a spring 96 returns the dogs 81 and 82 to normal position, thus permitting the escapement wheel 80 to feed one step, together 110 with the platen carriage 54, and thus effect a line-feeding movement of the work sheet 25.

By manipulating said key 71, the operator may make as many spaces as desired 115 between the vertical lines of writing; or the carriage-release key 85 may be used for the same purpose. Also depending from the rock shaft 93 is an arm 97, seen best at Fig. 4, which is provided for enabling the platen-rotating arm or handle 63 to effect automatically a line-feeding movement of the platen carriage. Said arm 63, for this purpose, is fast upon a horizontal rock shaft 98, which at its inner end carries an arm or 120 dog 99, to engage a pawl or trip 100, which is pivoted at 101 upon the lower end of said arm 97, and is normally held by a spring 102 against a stop 103 on said arm 97; the pawl having a shoulder 104 to engage said 130

- stop. During the downward stroke of the arm 63, the arm or dog 99 swings forward, as shown by the arrow at Fig. 4, and engages and drives the pawl 100 and the arm 97 bodily forward; these parts turning about the shaft 93 as if they were made in one piece, and causing the arm 94 on said shaft to swing rearwardly to operate the line-feeding dogs 81, 82.
- 10 Preferably, before the conclusion of the down or driving stroke of the arm 63, the point of the dog 99 escapes from the pawl 100, so that at any time thereafter the key 71 may be operated to perform its line-feeding function wholly independently of the said dog 99 or of the arm 63; the latter, of course, remaining in its depressed position until the types are again operated and the platen rotated for letter-feeding; said arm 63 gradually rising during the writing of the next vertical line on the work sheet. During the return stroke of the arm 63 and the dog 99, the dog engages and idly rotates the pawl 100 about the pivot 101; and after 25 the dog passes the pawl, the latter is snapped back to normal position by its spring 102.
- Certain of the type keys, as for instance key 1^a, are silent, that is, they are capable of printing but incapable of causing the 30 work-sheet to be character or letter-spaced, these keys being used for accenting or for building up alphabet characters, or for other purposes. The lever of each such silent key is arched upwardly at 70, Fig. 3, to clear the 35 second universal bar 38, so that said key lever cannot operate the alphabet character or letter-feeding dogs 29, 30. Its type bar, however, is provided with the usual heel 13 to operate the first universal bar 14 which 40 controls the ribbon-vibrating mechanism, so that the ribbon is thrown up to cover the printing point although the paper is not fed.
- Variations may be resorted to within the scope of the invention, and portions of the 45 improvements may be used without others.
- Having thus described my invention, I claim:
1. A typewriting machine constructed to write a language in which the written lines 50 extend vertically side by side down the page, comprising a horizontally-arranged, revolvable platen adapted to take in and hold a work-sheet introduced head first in the ordinary manner into the machine, a set of alphabet types constructed to make upright imprints upon said sheet, a system of alphabet keys for operating said types, and means 55 controlled by said system of alphabet keys for causing a step-by-step, rotary letter-spacing movement of said platen upon the actuation of said keys, whereby the successive imprints made by the types are disposed one below another in normal reading position in the written line.
2. A typewriting machine constructed to 65 write a language in which the written lines extend vertically side by side down the page, comprising a horizontally-arranged, revolvable platen adapted to take in and hold a work-sheet introduced head first in the ordinary manner into the machine, a set of alphabet types constructed to make upright imprints upon said sheet, a system of alphabet keys for operating said types, a spring 70 connected to rotate said platen forwardly, an escapement connected with said spring and controlled by said keys for causing a step-by-step, rotary letter-spacing movement of said platen by said spring upon the actuation of said keys, whereby the successive imprints made by the types are disposed one below another in proper position in the written line, and manually-operable means to rotate said platen backwardly in opposition to said spring, to begin a new line of 80 writing.
3. A typewriting machine constructed to 75 write a language in which the written lines extend vertically side by side down the page, comprising a horizontally-arranged, revolvable platen adapted to take in and hold a work-sheet introduced head first in the ordinary manner into the machine, a set of alphabet types constructed to make upright imprints upon said sheet, a system of alphabet keys for operating said types, a spring 85 connected to rotate said platen forwardly, an escapement connected with said spring and controlled by said keys for causing a step-by-step, rotary letter-spacing movement of said platen upon the actuation of said keys, whereby the successive imprints made by the types are disposed one below another in proper position in the written line, a carriage whereon said platen 90 is mounted to move the same endwise for line-spacing, and means for controlling the line-spacing movement of said carriage.
4. A typewriting machine constructed to 95 write a language in which the written lines 100 extend vertically side by side down the page, comprising a horizontally-arranged, revolvable platen adapted to take in and hold a work-sheet introduced head first in the ordinary manner into the machine, a set of alphabet types constructed to make upright imprints upon said sheet, a system of alphabet keys for operating said types, a spring 105 connected to rotate said platen forwardly, an escapement connected with said spring and controlled by said keys for causing a step-by-step, rotary letter-spacing movement of said platen upon the actuation of said keys, whereby the successive imprints made by the types are disposed one below another in proper position in the written line, a carriage for moving said platen endwise for line-spacing, and means 110

for simultaneously effecting a line-spacing movement of said carriage and a backward rotation of said platen.

5. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a carriage for moving said platen endwise for line-spacing, and feeding mechanism connecting said system of alphabet keys and said platen for imparting a step-by-step, rotary letter-spacing movement in a forward direction to said platen upon the actuation of said keys, whereby the successive imprints made by the types are disposed one below another in proper position in the written line, said feeding mechanism including a platen-driving spring, a member mounted upon the frame of the machine and connected with said spring to be driven thereby, and members coöperative with the first-named member mounted upon the carriage to travel with the same and extending to the platen to control the rotation thereof.
6. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a carriage for moving said platen endwise for line-spacing, and feeding mechanism connecting said system of alphabet keys and said platen for imparting a step-by-step, rotary letter-spacing movement in a forward direction to said platen upon the actuation of said keys, whereby the successive imprints made by the types are disposed one below another in proper position in the written line, said feeding mechanism including a platen-driving spring, a member mounted upon the frame of the machine and connected with said spring to be driven thereby, and members coöperative with the first-named member mounted upon the carriage to travel with the same and extending to the platen to control the rotation thereof, said carriage members being maintained connected with said frame member during movement of the carriage.
7. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a platen-driving spring, a train of gearing extending from said spring to said platen, and an escapement connected with said spring and controlled by said system of alphabet keys for causing a step-by-step, rotary letter-spacing movement of said platen in a forward direction by said spring upon the actuation of said keys, whereby the successive imprints of the types are disposed one below another in proper position in the written line.
8. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, a platen-driving spring, a train of gearing extending from said spring to said platen, an escapement connected with said spring and controlled by said system of alphabet keys for causing a step-by-step, rotary letter-spacing movement of said platen in a forward direction by said spring upon the actuation of said keys, whereby the successive imprints made by the types are disposed one below another in proper position in the written line, and means for moving said carriage and platen endwise, for line-spacing the latter.
9. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, a platen-driving spring, a train of gearing extending from said spring to said platen, an escapement connected with said spring and controlled by said system of alphabet keys for causing a step-by-step, rotary letter-spacing movement of said platen in a forward direction by said spring upon the actuation of said keys, whereby the successive imprints made by the types are disposed one below another in proper position in the written line, and means for moving said carriage and platen endwise, to line-space

the latter; said train of gearing including a couple, of which one member is mounted on the carriage to travel therewith, and the other member on the machine frame, said members being constructed to maintain connection during the travel of the carriage.

10. A machine of the class described, comprising a set of keys, a set of types controlled thereby, a revolute platen extending in a direction perpendicular to the line of writing, a carriage for said platen to move the latter endwise, a spring upon the framework of the machine, a key-controlled escapement mechanism connected to said 15 spring, and a train of gearing extending from the spring to the platen to turn the latter, said train including both an elongated barrel pinion mounted upon the framework of the machine, and also two branch-trains of 20 gears mounted on the carriage at the ends of the platen and extending to the platen, and each including a gear to mesh with said barrel pinion.

11. A machine of the class described, comprising a set of keys, a set of types controlled thereby, a revoluble platen extending in a direction perpendicular to the line of writing, a carriage for said platen to move the latter endwise, a spring upon the framework of the machine, a key-controlled escapement mechanism connected to said spring, and a train of gearing extending from the spring to the platen to turn the latter, said train including both an elongated barrel pinion mounted upon the framework of the machine, and also two branch-trains of gears mounted on the carriage at the ends of the platen and extending to the platen, and each including a gear to mesh with said barrel pinion, the length of said barrel pinion being such that either one or the other of said gears may run out of engagement with said barrel pinion while the other gear remains in engagement therewith.

45 12. A typewriting machine constructed to write a language in which the written lines extend vertically side by side down the page, comprising a horizontally-arranged, revolvable platen adapted to take in and hold a
50 work-sheet introduced head first in the ordinary manner into the machine, a set of alphabet types constructed to make upright imprints upon said sheet, a system of alphabet keys for operating said types, a traveling
55 carriage whereon said platen is mounted, a platen-driving spring, a train of gearing extending from said spring to said platen, an escapement connected with said spring and controlled by said system of alphabet keys
60 for causing a step-by-step, rotary letter-spacing movement of said platen in a forward direction by said spring upon the actuation of said keys, whereby the successive imprints made by the types are disposed one
65 below another in proper position in the writ-

ten line, and means for moving said carriage and platen endwise, to line-space the latter; said train of gearing including means to maintain the connection between the spring and the platen during the travel of the carriage in line-spacing direction. 70

13. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a platen-driving spring, a train of gearing extending from said spring to said platen, an escape-
ment connected with said spring and controlled by said system of alphabet keys for causing a step-by-step, rotary letter-spacing movement of said platen by said spring upon the actuation of said keys, whereby the successive imprints made by the types are disposed one below another in proper position in the written line, and a handle connected to rotate the platen backwardly in opposition to said spring, to begin a new line of writing.

14. A typewriting machine constructed to 95
write a language in which the written lines
extend vertically side by side down the page,
comprising a horizontally-arranged, revolu-
ble platen adapted to take in and hold a
work-sheet introduced head first in the or-
dinary manner into the machine, a set of
100 alphabet types constructed to make upright
imprints upon said sheet, a system of alpha-
bet keys for operating said types, a traveling
carriage whereon said platen is mounted, a
platen-driving spring, a train of gearing ex-
tending from said spring to said platen, an
escapement connected with said spring and
controlled by said system of alphabet keys
105 for causing a step-by-step, rotary letter-
spacing movement of said platen by said
spring upon the actuation of said keys,
whereby the successive imprints made by the
types are disposed one below another in
proper position in the written line, means
110 for moving said carriage and platen end-
wise, to line-space the latter, and a handle
connected to rotate the platen backwardly
in opposition to said spring, to begin a new
line of writing.

15. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a

- traveling carriage whereon said platen is mounted, feeding mechanism including a platen-driving spring connecting said system of alphabet keys and said platen for imparting a step-by-step, rotary letter-spacing movement to said platen in a forward direction upon the actuation of said keys, whereby the successive imprints made by the types are disposed one below another in proper position in the written line, and a key independent of the alphabet keys for effecting a step-by-step, endwise movement of said carriage and platen while the latter is held in any rotative position, to line-space the platen.
16. A typewriting machine constructed to write a language in which the written lines extend vertically side by side down the page, comprising a horizontally-arranged, revoluble platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism including a platen-driving spring connecting said system of alphabet keys and said platen for imparting a step-by-step, rotary letter-spacing movement to said platen in a forward direction upon the actuation of said keys, whereby the successive imprints made by the types are disposed one below another in proper position in the written line, and manually-controlled means for directly and positively rotating said platen backwardly, to begin a new line of writing and to wind up said spring.
17. A typewriting machine constructed to write a language in which the written lines extend vertically side by side down the page, comprising a horizontally-arranged, revoluble platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism including a platen-driving spring connecting said system of alphabet keys and said platen for imparting a step-by-step, rotary, letter-spacing movement to said platen in a forward direction upon the actuation of said keys, whereby the successive imprints made by the types are disposed one below another in proper position in the written line, a manually-operable device for directly and positively rotating said platen backwardly to begin a new line of writing and to wind up said spring controlled by said manually-operable device for effecting an endwise movement of said carriage and platen to line-space the latter.
18. A typewriting machine constructed to write a language in which the written lines extend vertically side by side down the page, comprising a horizontally-arranged, revoluble platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism including a platen-driving spring connecting said system of alphabet keys and said platen for imparting a step-by-step, rotary, letter-spacing movement to said platen in a forward direction upon the actuation of said keys, whereby the successive imprints made by the types are disposed one below another in proper position in the written line, and manually-controlled means for directly and positively rotating said platen backwardly, to begin a new line of writing and to wind up said spring.
19. A typewriting machine constructed to write a language in which the written lines extend vertically side by side down the page, comprising a horizontally-arranged, revoluble platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, a manually-controlled device for rotating said platen backwardly, to begin a new line of writing, and for effecting an endwise movement of said carriage and platen, to line-space the latter, and a separate key for effecting the line-spacing movement of said carriage independently of said manually-controlled device.
20. A typewriter machine constructed to write a language in which the written lines extend vertically side by side down the page, comprising a horizontally-arranged, revoluble platen adapted to take in and hold a work-sheet introduced head first in the ordinary manner into the machine, a set of alphabet types constructed to make upright imprints upon said sheet, a system of alpha-

bet keys for operating said types, a traveling carriage whereon said platen is mounted, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, and two separate, manually-controlled devices connected to effect, independently of each other, an endwise movement of said carriage and said platen, to line-space the latter; one of said devices being also connected to rotate said platen backwardly, to begin a new line of writing.

21. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, means connected with said carriage for moving the same and said platen endwise, to line-space the latter, a manually-operable device for rotating said platen backwardly, to begin a new line of writing, said manually-operable device being connected with the last-named means to control the operation thereof, and a separate key connected to control the operation of said last-named means independently of said manually-operable device.

22. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, a spring connected with said carriage for moving the same and said platen end-

wise, to line-space the latter, an escapement for controlling said spring, a manually-operable device for rotating said platen backwardly, to begin a new line of writing, and means connected to said manually-operable device for operating said escapement.

23. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, a spring connected with said carriage for moving the same and said platen endwise, to line-space the latter, an escapement for controlling said spring, a manually-operable device for rotating said platen backwardly, to begin a new line of writing, means connected to said manually-operable device for operating said escapement, and a separate key connected to operate said escapement independently of said manually-operable device.

24. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a traveling carriage whereon said platen is mounted, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, means connected with said carriage for moving the same and said platen from left to right, to line-space said platen, an escapement for controlling the movement of said carriage in such direction, and a manually-operable device for rotating said platen backwardly, to begin a new line of writing, said manually-operable device being connected to operate said escapement.

25. A typewriting machine constructed to write a language in which the written lines extend vertically side by side down the

page, comprising a horizontally-arranged, revolute platen adapted to take in and hold a work-sheet introduced head first in the ordinary manner into the machine, a set of 5 alphabet types constructed to make upright imprints upon said sheet, a system of alphabet keys for operating said types, a traveling carriage whereon said platen is mounted, feeding mechanism connecting said system of alphabet keys and said platen for imparting a step-by-step, rotary, letter-spacing movement to said platen upon the actuation of said keys, whereby the successive imprints made by the types are disposed one 10 below another in proper position in the written line, means connected with said carriage for moving the same and said platen from left to right, to line-space said platen, an escapement for controlling the movement 15 of said carriage in such direction, a manually-operable device for rotating said platen backwardly, to begin a new line of writing, said manually-operable device being connected to operate said escapement, 20 and a separate key connected to operate said escapement independently of said manually-operable device.

26. A typewriting machine constructed to write a language in which the written lines 30 extend vertically side by side down the page, comprising a horizontally-arranged, revolute platen adapted to take in and hold a work-sheet introduced head first in the ordinary manner into the machine, a set of 35 alphabet types constructed to make upright imprints upon said sheet, a system of alphabet keys for operating said types, a line-spacing carriage whereon said platen is mounted, a platen-driving spring, an escapement connected with said spring and 40 controlled by said system of alphabet keys for causing a step-by-step, rotary, letter-spacing movement of said platen in a forward direction by said spring upon the 45 actuation of said keys, whereby the successive imprints made by the types are disposed one below another in proper position in the written line, a non-printing key connected to impart a rotary, word-spacing 50 movement in a forward direction to said platen, and a key connected to control the line-spacing movement of said carriage while the platen is held in any rotative position under the control of said escapement.

55. 27. A typewriting machine constructed to write a language in which the written lines 60 extend vertically side by side down the page, comprising a horizontally-arranged, revolute platen adapted to take in and hold a work-sheet introduced head first in the ordinary manner into the machine, a set of 65 alphabet types constructed to make upright imprints upon said sheet, a system of alphabet keys for operating said types, a line-spacing carriage whereon said platen is

mounted, a platen-driving spring, an escapement connected with said spring and controlled by said system of alphabet keys for causing a step-by-step, rotary, letter-spacing movement of said platen in a forward 70 direction by said spring upon the actuation of said keys, whereby the successive imprints made by the types are disposed one below another in proper position in the written line, a non-printing key connected to impart a rotary, word-spacing 75 movement in a forward direction to said platen, a spring connected to drive said carriage from left to right, a spacing mechanism controlling the drive of said carriage 80 by said spring, and a key for operating said spacing mechanism and causing a step-by-step movement of the carriage while the platen is held in any rotative position under the control of said escapement. 85

28. The combination of a revolute platen, a character-feeding mechanism to control the revolution thereof, a manually operated device connected to positively rotate the platen back for beginning a new line, and 90 means connected to be operated by said manually operated device for line-spacing the platen.

29. The combination of a revolute platen, a character-feeding mechanism to control 95 the revolution thereof, a manually controlled device for rotating the platen back for beginning a new line, and means connected to said manually controlled device for line-spacing the platen, said line-spacing means including a trip which automatically disconnects said manually controlled device 100 when it has line-spaced the platen.

30. The combination of a revolute platen, a character-feeding mechanism to control 105 the revolution thereof, a manually controlled device for rotating the platen for beginning a new line, means connected to said manually controlled device for line-spacing the platen, said line-spacing means including a trip which automatically disconnects said manually controlled device 110 when it has line-spaced the platen, and a key for line-spacing the platen independently of said manually controlled device. 115

31. The combination of a platen, type keys, a spring for rotating the platen, character-feeding mechanism operated by said type keys for controlling the rotation of the platen by said spring, a carriage for said platen, a spring for driving said carriage, line-spacing mechanism for controlling the movements of the carriage, a key for operating said line-spacing mechanism, a manually controlled device for rotating the platen backwardly to begin a new line of writing, and means for enabling said manually controlled device first to operate and then to release said line-spacing mechanism. 120

32. The combination of a platen, type 125

- keys, a spring for rotating the platen, character-feeding mechanism operated by said type keys for controlling the rotation of the platen by said spring, a carriage for said platen, a spring for driving said carriage, line-spacing mechanism for controlling the movements of the carriage, a key for operating said line-spacing mechanism, a manually controlled device for rotating the platen backwardly to begin a new line of writing, said line-spacing mechanism including an arm having a trip, and said manually controlled device including an arm having a dog to engage said trip and operate the line-spacing mechanism during one stroke of the manually controlled device, and to pass freely by said trip during the return stroke thereof and release the same during the first stroke.
33. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, a manually-controlled device for rotating the platen backwardly to begin a new line of writing, means connected to said manually-controlled device for line-spacing said platen; said line-spacing means including a trip which automatically disconnects said manually-controlled device when it has line-spaced the platen.
34. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, feeding mechanism connecting said system of alphabet keys and said platen for imparting a step-by-step, rotary, letter-spacing movement to said platen upon the actuation of said keys, whereby the successive imprints made by the types are disposed one below another in proper position in the written line, a traveling carriage wherein said platen is mounted, a spring for driving said carriage, line-spacing mechanism for controlling the movement of the carriage by said spring, and a manually-controlled device for rotating said platen backwardly to begin a new line of writing, said line-spacing mechanism including an arm having a trip, and said manually-controlled device including a member having a dog to initially engage said trip and operate the line-spacing manually-controlled device for line-spacing the platen, said line-spacing means including a trip which automatically disconnects said manually-controlled device when it has line-spaced the platen, and a key for line-spacing the platen independently of said manually-controlled device.
35. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a feeding mechanism connecting said system of alphabet keys and said platen for imparting a step-by-step, rotary, letter-feeding movement to said platen upon the actuation of said keys, whereby the successive imprints made by the types are disposed one below another in proper position in the written line, a traveling carriage whereon said platen is mounted, a spring for driving said carriage, line-spacing mechanism for controlling the movement of the carriage by said spring, a manually-controlled device for rotating said platen backwardly to begin a new line of writing, means for enabling said manually-controlled device first to operate and then to release said line-spacing mechanism, and a key for operating said line-spacing mechanism independently of said manually-controlled device.
36. A typewriting machine constructed to write a language in which the written lines extend vertically side by side down the page, comprising a horizontally-arranged, revolute platen adapted to take in and hold a work-sheet introduced head first in the ordinary manner into the machine, a set of alphabet types constructed to make upright imprints upon said sheet, a system of alphabet keys for operating said types, a feeding mechanism connecting said system of alphabet keys and said platen for imparting a step-by-step, rotary, letter-feeding movement to said platen upon the actuation of said keys, whereby the successive imprints made by the types are disposed one below another in proper position in the written line, a traveling carriage wherein said platen is mounted, a spring for driving said carriage, line-spacing mechanism for controlling the movement of the carriage by said spring, and a manually-controlled device for rotating said platen backwardly to begin a new line of writing, said line-spacing mechanism including an arm having a trip, and said manually-controlled device including a member having a dog to initially engage said trip and operate the line-spacing

mechanism and subsequently release said trip during one stroke of said manually-controlled device, and to pass freely by said trip during the return stroke thereof.

5 37. The combination of a revoluble platen, character-feeding mechanism to control the rotation thereof, a manually-controlled device for rotating the platen backwardly to begin a new line of writing, means connected to said manually-controlled device for line-spacing the platen, and a key for operating said line-spacing means independently of said manually-controlled device.

10 38. The combination of a platen, type keys, a spring for rotating the platen, character-feeding mechanism operated by said type keys for controlling the rotation of said platen by said spring, a carriage for said platen, a spring for driving said carriage, line-spacing mechanism for controlling the movements of the carriage, a manually-controlled device for rotating the platen backwardly to begin a new line of writing, and means for enabling said manually-controlled device first to operate and then to release said line-spacing mechanism.

15 39. The combination of a platen, type keys, a spring for rotating the platen, character-feeding mechanism operated by said type keys for controlling the rotation of the platen by said spring, a carriage for said platen, a spring for driving said carriage, line-spacing mechanism for controlling the movements of the carriage, and a manually-controlled device for rotating the platen backwardly to begin a new line of writing, said line-spacing mechanism including an arm having a trip, and said manually-controlled device including a member having a dog to initially engage said trip and operate the line-spacing mechanism and subsequently release said trip during one stroke of the manually-controlled device, and to pass freely by said trip during the return stroke thereof.

20 40. A typewriting machine constructed to write a language in which the written lines extend vertically side by side down the page, comprising a horizontally-arranged, revoluble platen adapted to take in and hold a work-sheet introduced head first in the ordinary manner into the machine, a set of alphabet types constructed to make upright imprints upon said sheet, a system of alphabet keys for operating said types, a feeding mechanism connecting said system of alphabet keys and said platen for imparting a step-by-step, rotary, letter-feeding movement to said platen upon the actuation of said keys, whereby the successive imprints made by the types are disposed one below another in proper position in the written line, means for concomitantly rotating the platen backwardly, to begin a new line of

writing, and moving it endwise for line-spacing, and a key for moving said platen endwise for line-spacing independently of said backwardly-rotating means.

41. A typewriting machine comprising a revoluble platen, a set of alphabet types, a system of alphabet keys for operating said types, a platen-driving spring, a train of gearing leading from said spring to said platen for rotating the latter, an escapement for controlling the driving of said gearing by said spring, to letter-space the platen, gearing associated with the first-named gearing to reverse the direction of movement thereof, for rotating the platen backwardly, to begin a new line of writing, and for rewinding said spring, and a manually-operable device for driving the second-named gearing.

42. A typewriting machine comprising a revoluble platen, a line-spacing carriage whereon the same is mounted, a set of alphabet types, a system of alphabet keys for operating said types, a platen-driving spring, a train of gearing leading from said spring to said platen for rotating the latter, an escapement controlled by said system of alphabet keys for controlling the driving of said gearing by said spring, to letter-space the platen at each key-stroke, gearing associated with the first-named gearing to reverse the direction of movement thereof, for rotating the platen backwardly to begin a new line of writing, line-spacing mechanism for controlling the movements of said carriage, and means for concomitantly driving the second-named gearing and actuating said line-spacing mechanism.

43. A typewriting machine comprising a revoluble platen, a line-spacing carriage whereon the same is mounted, a set of alphabet types, a system of alphabet keys for operating said types, a platen-driving spring, a train of gearing leading from said spring to said platen for rotating the latter, an escapement controlled by said system of alphabet keys for controlling the driving of said gearing by said spring, to letter-space the platen at each key-stroke, gearing associated with the first-named gearing to reverse the direction of movement thereof, for rotating the platen backwardly to begin a new line of writing, line-spacing mechanism for controlling the movements of said carriage, and a manually-operable device for driving the second-named gearing, said device having means connected to it for actuating said line-spacing mechanism.

44. A typewriting machine comprising a revoluble platen, a set of alphabet types, a system of alphabet keys for operating said types, a platen-driving spring, a rotatable barrel wherein said spring is disposed, a

pair of gears fixed to said barrel, a vertical shaft, a pair of gears on said shaft, one of said shaft gears meshing with one of said barrel gears, gearing connecting the 5 other shaft gear with said platen to rotate the latter, an escapement connected with said barrel for effecting the rotary, letter-spacing movement of said platen by said spring, a pair of connected idle gears, one 10 of which meshes with the other barrel gear, and a manually-operable, toothed element engaging the other idle gear to reverse the direction of rotation of said barrel and its gear connections with said platen, for rotating said platen backwardly to begin a new line of writing, and for rewinding said spring.

45. A typewriting machine comprising a revoluble platen, a set of alphabet types, 20 a system of alphabet keys for operating said types, a platen-driving spring, a rotatable barrel wherein said spring is disposed, a pair of gears fixed to said barrel, a vertical shaft, a pair of gears on said shaft, one 25 of said shaft gears meshing with one of said barrel gears, gearing connecting the other shaft gear with said platen to rotate the latter, an escapement connected with said barrel for effecting the rotary, letter-spacing 30 movement of said platen by said spring, and manually-operable gearing associated with the other barrel gear to reverse the direction of rotation of said barrel and its gear connections with said platen, for rotating said 35 platen backwardly to begin a new line of writing, and for rewinding said spring.

46. A typewriting machine comprising a revoluble platen, a set of alphabet types, a system of alphabet keys for operating said 40 types, a traveling carriage whereon said platen is mounted, feeding mechanism connecting said system of alphabet keys and said platen for imparting a step-by-step, rotary, letter-feeding movement to said 45 platen upon the actuation of said keys, a carriage-driving spring, an escapement for controlling the drive of said carriage by said spring, a member for operating said escapement, a manually-operable lever arranged to actuate said member and to rotate 50 the platen to starting position, a rod connected at one end to operate said member independently of said lever, a lever connected to the other end of said rod, and a key 55 connected to operate said last-mentioned lever,

47. A typewriting machine comprising a revoluble platen, a set of alphabet types, a system of alphabet keys for operating said 60 types, a traveling carriage whereon said platen is mounted, feeding mechanism connecting said system of alphabet keys and said platen for imparting a step-by-step, rotary, letter-feeding movement to said

platens upon the actuation of said keys, a carriage-driving spring, an escapement for controlling the drive of said carriage by said spring, a member for operating said escapement, a trip connected to said member, a rock shaft, a dog mounted on 70 said shaft, and a handle connected to operate said shaft, said dog being arranged, during one stroke of said handle, to initially engage said trip and actuate said member and to subsequently release the trip, and to pass 75 freely by said trip during the return stroke of said handle.

48. A typewriting machine comprising a revoluble platen, a set of alphabet types, a system of alphabet keys for operating said 80 types, a traveling carriage whereon said platen is mounted, feeding mechanism connecting said system of alphabet keys and said platen for imparting a step-by-step, rotary, letter-feeding movement to said platen 85 upon the actuation of said keys, a carriage-driving spring, an escapement for controlling the drive of said carriage by said spring, a member for operating said escapement, a trip connected to said member, a 90 rock shaft, a dog mounted on said shaft, a handle connected to operate said shaft, said dog being arranged, during one stroke of said handle, to initially engage said trip and actuate said member and to subsequently release said trip and to pass freely 95 by said trip during the return stroke of said handle, and means for operating said escapement independently of said handle embodying a rod connected at one end to operate said member, a lever connected to the other end of said rod, and a key connected to operate said lever.

49. In a typewriting machine, the combination of a set of alphabet types constructed 105 to make upright imprints upon a worksheet, a system of alphabet keys for operating said types, a horizontal, revoluble platen, a carriage whereon the platen is mounted, a motor for rotating the platen, an 110 escapement controlling the rotation of said platen by said motor, and a driving train leading from said motor to said platen, said train including an elongated barrel-pinion mounted upon the framework of the machine, and two branch trains of gears mounted on the carriage at the ends of the platen and extending to the latter, each of said branch trains including a gear to mesh with 115 said barrel-pinion.

50. In a typewriting machine, the combination of a set of alphabet types constructed to make upright imprints upon a worksheet, a system of alphabet keys for operating said types, a horizontal, revoluble 125 platen, a carriage whereon the platen is mounted, a motor for rotating the platen, an escapement controlling the rotation of said

- platen by said motor, and a driving train leading from said motor to said platen, said train including an elongated barrel-pinion mounted upon the framework of the machine, and two branch trains of gears mounted on the carriage at the ends of the platen and extending to the latter, each of said branch trains including a gear to mesh with said barrel-pinion; the length of said barrel-pinion being such that either one or the other of said gears may run out of engagement with said barrel-pinion while the other gear remains in engagement therewith.
- 5 51. In a typewriting machine constructed to write a language in which the written lines extend vertically side by side down the page, the combination of a horizontal, revolute platen, a spring for rotating said platen
- forwardly, an escapement for controlling 20 the rotation of said platen by said spring to effect a rotary, step-by-step, letter-feeding movement of said platen, and a manually-controlled device geared to the platen for positively rotating said platen backwardly to begin a new line of writing and for rewinding said spring when said device is moved in one direction, said device being moved step-by-step in the opposite direction during said letter-feeding movement 25 30 of the platen, and said escapement operable to hold the platen in any intermediate position to which it may be rotated backwardly by said device.
